DESIGN.

H. C. BASCOM & F. RITCHIE.

PARLOR STOVE.

No. 15,646.

Patented Dec. 30, 1884.

UNITED STATES PATENT OFFICE.

H. CLAY BASCOM AND FRANCIS RITCHIE, OF TROY, NEW YORK, ASSIGNEES
TO SAID H. CLAY BASCOM.

DESIGN FOR A PARLOR-STOVE.

SPECIFICATION forming part of Design No. 15,646, dated December 30, 1884.

Application filed October 20, 1884. Term of patent 7 years.

To all whom it may concern:

Be it known that we, H. CLAY BASCOM and FRANCIS RITCHIE, citizens of the United States, residing in the city of Troy, in the county of Rensselaer and State of New York, have jointly invented and produced a new and original Design for a Parlor-Stove, of which the following is a specification, reference being had to the accompanying engraving of a stove having said design.

This design embraces several new and distinctive parts and combinations of parts which go to make up the whole design, as hereinafter specified. The vase represented on the cover of the stove is not a part of this design. One part is the shape and ornamentation of the cover A, consisting of the concave molding *a*, lower border *b*, and the intermediate convexly-curved portion, *c*, having the compound downwardly-spreading scroll-form ornaments *c'* and the intermediate lower upwardly-spreading ornaments, *c''*. Another part is the ornamentation of the rectangular panels B of the cylindrical upper section, consisting of the corner ornaments, *d*, each having the club-form radiations extending from the trifid angle part, and the side ornamentations, *e*, each having the central semi-rosette with flaring bat-form extensions along the border of the panel from opposite sides of the semi-rosette, and the rectangular panel ornament C, having the series of incut radiations *f* *f'* *f''*, all in the form of a rhomb, and the incut ornamentations *g* in the rectangular corner parts. Another part embraces the shape and ornamentation of the illuminating-doors D, each being of an outwardly-convex trapezoidal form, and having the three rows *h* *i* *j* of trapezoidal openings, which are separated vertically by the three bars *k*, and horizontally by bars, of which the upper ones, *l*, have semi-rosettes *m* in the openings of the upper row, and the lower bars, *n*, have the circular ornaments *n'* in one lower corner of the openings of the middle horizontal row, and the bars *o* crossing the openings of the lower row. Another part embraces the shape and ornamentation of the lower illumination-doors, F, each being in the form of a parallelogram curved

convexly in the lengthwise direction, and having the upper row of three rectangular light-openings, *s*, with the arch *s'* and semi-rosette *s''* in each, and the six rectangular light-openings, *t*, in the lower row. Another distinctive part is the shape and ornamentation of the legs, consisting of the ornamented angular cap part *x*, and the downwardly-contracted and concavely-curved lower angular portion *y*, having the circular corner ornaments, *y'*, and the middle leaf ornament, *z*.

The whole design embraces the shape and ornamentation of the cover A, panels B C, doors D F, casing E, having the parts *p* *q* *r*, base-section G, having the parts *u* *u'* *v*, plates H, having the ornaments *w* *w'* *w''*, the division-plates I J K, and the legs.

We claim as new—

1. In a design for a stove, the shape and ornamentation of the cover A, consisting of the parts *a* *b* *c* *c'* *c''*, as shown and described.

2. In a design for a stove, the ornamentation of the rectangular panels B of the cylindrical upper section, consisting of the parts *d* *e* *C* *f* *f'* *f''* *g*, substantially as shown and described.

3. In a design for a stove, the shape and ornamentation of the illuminating-doors D, embracing the parts *h* *i* *j* *k* *l* *m* *n* *n'* and *o*, as set forth.

4. In a design for a stove, the shape and ornamentation of the illuminating-doors F, embracing the parts *s* *s'* *s''* and *t* as set forth.

5. In a design for a stove, the shape and ornamentation of the legs, embracing the parts *x* *y* *y'* *z*, as set forth.

6. The design for a stove, embracing the parts A B C D E F G H I J K and the legs, shaped and ornamented substantially as shown.

In testimony whereof we hereunto set our hands, in the presence of two subscribing witnesses, this 17th day of October, 1884.

H. CLAY BASCOM.
FRANCIS RITCHIE.

Witnesses:

CHARLES H. BENEDICT,
JAMES A. GILMAN.
